UNITED STATES PATENT OFFICE.

MELCHIOR ZWICKY, OF WYOMISSING, PENNSYLVANIA, ASSIGNOR TO TEXTILE MACHINE WORKS, OF WYOMISSING, PENNSYLVANIA, A CORPORATION OF PENNSYLVANIA.

JACK MECHANISM FOR FULL-FASHIONED KNITTING MACHINES.

1,371,535.

Specification of Letters Patent. Patented Mar. 15, 1921.

Application filed March 17, 1920. Serial No. 366,679.

To all whom it may concern:

Be it known that I, MELCHIOR ZWICKY, a citizen of the United States, residing at Wyomissing, in the county of Berks and 5 State of Pennsylvania, have invented certain new and useful Improvements in Jack Mechanism for Full-Fashioned Knitting Machines, of which the following is a specification.

10 My invention relates to full-fashioned knitting machines, and particularly to the jack mechanism thereof whereby the sinkers are properly projected. It is fully set forth in connection with the accompanying 15 drawing and the novel features are specifically pointed out in the claim.

Figure 1 is a partial cross-sectional view of the top portion of a straight knitting machine, showing the mounted sinkers and the 20 operating slur-cam therefor, in connection with my improved jack mechanism.

Fig. 2 is a partial rear-face view of the jack mechanism, with parts broken away; and Fig. 3 is a partial plan view of the 25 same.

The movably mounted sinkers 10, in the sinker head 11, are projected against the verge plate 12, as usual, by action of the sliding slur-cam 13 on slur-cam bar 14; this 30 being effected through corresponding series of interposed jacks 15, which are swung on axle 16 to press their upper ends 17 against the sinkers. The object of my improved construction is to provide for satisfactorily 35 insuring definite accurate movement of the sinkers, which is absolutely required for uniform knitting, and at the same time avoiding objectionable wear of the parts in effecting such movement.

40 The jack axle 16 is fixed in end pieces 20 of the jack bed 21, and the sheet-material jacks 15 mounted thereon are swung between a corresponding series of spacing plates 22, which are held to the bed 21 by a 45 clamping bar 23, with the forward and rear edges thereof engaged respectively in slots of a forward bar 25 and of a rear bar 26 extending between the end pieces 20. An intermediate rear bar 27 safely retains the

conveniently placed jacks upon the axle 16, 50 leaving space above it for passage of the slur-cam 13 into operating contact with the rear edges 28 of the jacks. Positive stopping of the forward movements of the jacks is provided for, with extended stopping 55 contact, by adapting and locating said forward bar 25 to cause the front edges 29 of the jacks to abut squarely against the ribbed inner face thereof when the sinker-contacting heads of the jacks have been properly 60 projected, as shown in Fig. 1; said inner face being accurately finished and set parallel to the verge plate, so that the sinkers will be uniformly positioned when the jacks are thus pressed against it, and a long edge- 65 contact of the latter will be provided for wear. With positive and accurate stopping of the jack movements thus insured, required adjustment of the slur-cam to effect such movement is simplified, and it is possible to so mount the same as to provide for such a yielding of the cam upon contact 70 of the jacks with the stop-bar 25, as will in any case prevent undue strains and wear. The required accurate setting relatively of 75 this stop-bar and the verge plate is readily secured and maintained, and the latter prevents any otherwise possible throwing of the sinkers beyond the limit of positive movement set by the stop bar, so that any 80 hurtful variation from absolute uniformity of the projected sinker positions cannot occur.

What I claim is:

In a straight knitting machine, the combination with a suitably mounted series of sinkers and an operating slur cam therefor, of an interposed corresponding series of pivotally carried sinker-contacting jacks, a fixed forward stop-bar against which said 90 jacks are swung by the passing slur-cam to determinedly project the sinkers, a fixed rear retaining bar for said jacks, and fixed spacing plates for the jacks extending between said forward and rear bars. 95

In testimony whereof I affix my signature.

MELCHIOR ZWICKY.
